VARIABLE PITCH PROPELLER

Robert J. Ruths, Baltimore, Md., and Harry L. Dodson, United States Navy

Application August 20, 1938, Serial No. 225,890

3 Claims. (CL. 170—162)

(Granted under the act of March 3, 1883, as amended April 30, 1928; 370 O. G. 757)

This invention relates to variable pitch propellers and it has for its principal object the provision of a new and improved propeller or impeller for ships and pumps in which the pitch of the several blades will be varied automatically in accordance with the horsepower applied and the thrust exerted by the blade against a fluid environment.

With these and other objects in view, as well as other advantages that may be incident to the use of the improvements, the invention consists in the parts and combinations thereof herein-after set forth and claimed, with the understanding that the several necessary elements constituting the same may be varied in proportion and arrangement without departing from the nature and scope of the invention, as defined in the appended claims.

In order to make the invention more clearly understood, there are shown in the accompanying drawings, means for carrying the invention into practical use, without limiting the improvements in their useful application to the particular construction, which, for the purpose of explanation, have been made the subject of illustration.

In the accompanying drawings:

Fig. 1 is a longitudinal sectional view through a propeller hub embodying the invention;

Fig. 2 is a side elevational view with parts broken away of the structure shown in Fig. 1;

Fig. 3 is a transverse sectional view taken on line 3—3 of Fig. 2;

Fig. 4 is a longitudinal sectional view of a portion of the propeller shaft showing the coaxially extending torsion shaft;

Fig. 5 is a transverse sectional view taken on line 5—5 of Fig. 4; and

Figs. 6 and 7 are diagrammatic views showing the unbalanced construction of the leading and trailing edges of the propeller blade and the change in pitch of the blade caused thereby.

Referring to the drawings, a variable pitch propeller constructed according to the invention is shown as comprising a hub 10 having a forward portion 11 and an after portion 12 secured together by longitudinally extending bolts 13 and provided with a scarf joint 14 therebetween to prevent relative rotation of the parts and to relieve the bolts 13 from shearing strains. A hollow streamline hub cap 15 is secured to the after portion 12 of the hub by means of a nipple 16 provided on the former for screw threaded engagement with the latter and is prevented from becoming unscrewed by a lock screw 17 threaded into both the portion 12 and cap 15 in the plane of their contacting faces and functioning as a key therebetween. The forward end of the portion 11 of the hub is fixed to collar 18 formed on a section 19a of a main drive shaft by means of bolts

20 and is provided with a tapered bore 21 into which the rear end of the shaft 19a extends and is secured therein by a key 22.

The adjacent ends of the portions 11 and 12 of the hub are recessed to form a central gear chamber 23 and their marginal edges are also formed with complementary semicircular recesses providing a plurality of circumferentially arranged sockets 24, herein shown as constituting three in number. These sockets each open into the gear chamber 23 and also into an inner rearwardly elongated channel 25 formed in the after portion 12 of the hub (Figs. 1 and 2). A plurality of propeller blades 26 are mounted on the hub 10 and their root portions are each formed with a neck 27 which is journaled in the socket 24 and a collar 28 disposed within the associated channel 25 for preventing radial displacement of the blade but permitting the blade to rotate about a radially extending axis X. The collars 28 are each formed with a segmental bevel gear 29 which meshes with a single bevel pinion 30 disposed within the chamber 23, thus insuring that the blades 26 will move in unison when rotated about their axes X, in a manner herein-after to be described.

The pinion 30 is fixed to the rear end of a flexible torsion or quill shaft 31 which extends forwardly through an axial bore 32 formed in the section 19a of the main drive shaft. The extreme forward end of the torsion shaft 31 is fixed to an external circular spline 33 (Fig. 5) which interlocks with an internal spline surface formed in a collar 34'. Cooperating with the collar 34' is a second collar 34 which is preferably formed in two parts, as shown in Fig. 5, to permit it to be assembled on the shaft and is formed with an internal annular shoulder 35 (Fig. 4) for engagement with an external circumferential groove formed in the rear end of the section 19a of the main drive shaft. The halves of the collar 34 are secured by means of bolts 39 to a collar 36, which is fixed to the section 19a of the drive shaft by a key 37 and also to an annular flange 38 formed on a forward section 19b of the drive shaft, thus tying all of the parts together for rotation in unison, and anchoring the forward end of the torsion shaft 31 to the main drive shaft.

The rotation of each of the blades 26 of the propeller and the torsion exerted thereby upon the torsion shaft 31 is prevented from exceeding a predetermined maximum limit which is determined by the pitch of maximum efficiency, by means of a stop arm 40 (Fig. 2) which is provided on each of the collars 28 for abutting engagement with the side walls of the channel 25 within which such arm is located. Shims 41 may be secured to the sides of the stop arms to accurately limit the rotation of the blades within maximum and minimum pitches.

OPERATION: Let it be assumed that the propeller is at rest and exerts no force against its surrounding fluid environment. Under such conditions the blades of the propeller occupy positions of maximum pitch, as is diagrammatically illustrated in Fig. 6. If power is now applied gradually to the drive shaft, the force reacting against the trailing edge TE of each blade, which is of greater surface area than the leading edge LE thereof, will cause the blade to turn about its axis X in a counter-clockwise direction, decreasing its pitch and exerting a twisting strain upon the torsion shaft 31. The centrifugal action acting on the blades also aids in this forcing of the blades to a position of decreased pitch. As the horsepower is increased, this reactional force will correspondingly increase, and proportionally decrease the pitch of the blades until it reaches the pitch of maximum efficiency which will correspond to the horsepower of maximum efficiency applied to the propeller. When this point is reached, the stop arms 40 will engage the sides of the channels 25 and prevent any further turning movement of the blades and any further decrease in the strain transmitted to the torsion shaft 31. Conversely, as the horsepower applied to the propeller by the prime mover is decreased, the energy stored in the torsion shaft 31 will rotate the blades 26 of the propeller in a reverse direction so as to correspondingly increase the pitch of the blades. Thus, it will be seen that the pitch of the blades of the propeller is at all times in accordance with the applied horsepower and at the most efficient pitch for such horsepower.

It will be understood that the above description and accompanying drawings comprehend only the general and preferred embodiment of the invention and that various changes in construction, proportion, and arrangement of the parts may be made within the scope of the appended claims without sacrificing any of the advantages of the invention.

The invention described herein may be manufactured and/or used by or for the Government of the United States of America for governmental purposes without the payment of any royalties thereon or therefor.

We claim:

1. A variable pitch propeller comprising a hub; a blade mounted on said hub for rotation about a radially extending axis, the trailing edge of said blade located on one side of said axis having a greater surface area than the leading edge thereof located on the opposite side of said axis, the thrust exerted by the trailing edge of said blade thus tending to rotate said blade about said axis to decrease the pitch thereof; a hollow main shaft having an after section on which said hub is mounted and a forward engine section, said after section having an annular groove formed in its forward end and said engine section having a flange formed on its after end; a torsion shaft extending through the after section of said main shaft and having a splined portion formed on its forward end; a collar keyed to the forward end of the after section of said main shaft; a split ring disposed in engagement with said groove; an internally splined anchor member disposed in locking engagement with the splined portion of said torsion shaft, through bolts passing through said flange, anchor member, split ring and collar and rigidly securing the assembly together to prevent relative axial and rotary dis-

placement of the parts thereof; and gear means connecting the after end of said torsion shaft with said blade, whereby such rotational motion of said blade about said axis will transmit torsional strain to said torsion shaft and be opposed thereby, thus storing energy in said torsion shaft so as to rotate said blade in an opposite direction about said axis to increase the pitch of said blade with a decrease in the thrust exerted thereby.

2. A variable pitch propeller comprising a hub; a blade mounted on said hub for rotation about a radially extending axis, the trailing edge of said blade located on one side of said axis having a greater surface area than the leading edge thereof located on the opposite side of said axis, the thrust exerted by the trailing edge of said blade thus tending to rotate said blade about said axis to decrease the pitch thereof; a hollow main shaft having an after section on which said hub is mounted and a forward engine section, said after section having an annular groove formed in its forward end and said engine section having a flange formed on its after end; a torsion shaft extending through the after section of said main shaft and having a flange formed on its forward end; a collar keyed to the forward end of the after section of said main shaft; a split ring disposed in engagement with said groove; an anchor member disposed in locking engagement with the flange on said torsion shaft, means rigidly connecting said flanges, anchor member, split ring and collar to prevent relative axial and rotary displacement thereof; and gear means connecting the after end of said torsion shaft with said blade, whereby such rotational motion of said blade about said axis will transmit torsional strain to said torsion shaft and be opposed thereby, thus storing energy in said torsion shaft so as to rotate said blade in an opposite direction about said axis to increase the pitch of said blade with a decrease in the thrust exerted thereby.

3. A variable pitch propeller comprising a hub; a blade mounted on said hub for rotation about a radially extending axis, the trailing edge of said blade located on one side of said axis having a greater surface area than the leading edge thereof located on the opposite side of said axis, the thrust exerted by the trailing edge of said blade thus tending to rotate said blade about said axis to decrease the pitch thereof; a hollow main shaft having an after section on which said hub is mounted and a forward engine section, said after section having an annular groove formed in its forward end and said engine section having a flange formed on its after end; a torsion shaft extending through the after section of said main shaft and having a flange formed on its forward end; a collar keyed to the forward end of the after section of said main shaft; a split ring disposed in engagement with said groove; bolts passing through said flanges, split ring and collar and rigidly securing the assembly together to prevent relative axial and rotary displacement of the parts thereof; and gear means connecting the after end of said torsion shaft with said blade, whereby such rotational motion of said blade about said axis will transmit torsional strain to said torsion shaft and be opposed thereby, thus storing energy in said torsion shaft so as to rotate said blade in an opposite direction about said axis to increase the pitch of said blade with a decrease in the thrust exerted thereby.
